MAGAZINE BINDER

Herman T. Arends, Highland Park, Mich.

Application March 13, 1947, Serial No. 734,481

2 Claims. (Cl. 129—23)

1

The present invention relates to loose-leaf binders, that is, binders for magazines, pamphlets and single sheets to form a single volume.

Among the objects of the invention is to provide a simple, cheap, efficient binder that permits the binding of such articles without the necessity of previous careful preparation utilizing expensive and not always accessible punching devices.

Another object is a binder that permits the binding of such articles in which the perforations may be nail holes or the like.

Other objects will readily occur to those skilled in the art upon reference to the following description and the accompanying drawings in which

Fig. 1 is a perspective view of the operative portions of a binder made according to the present invention.

Fig. 2 is a view of one of the paper traversing elements.

Fig. 3 is an enlarged detail taken on line 3—3 of Fig. 1.

Fig. 4 is a section on line 4—4 of Fig. 3.

Fig. 5 is a view of the elements shown in Fig. 3 but in a different position.

Fig. 6 is a section on line 6—6 of Fig. 5.

Fig. 7 is a view similar to Fig. 1, but of a slightly modified form.

In the drawing, the binder is shown as consisting of a suitable cover 10 having at each side of the back 10A, a strip 11 of suitable stiff durable material, such as metal, vulcanized fiber or other suitable material, hinged or fixed rigidly to the back 10A.

Each of the strips 11 will be provided with two or more spaced openings 12 preferably located along the median line and so located that each is opposite an opening in the other strip. These openings 12 are for the reception of wire elements 15, preferably piano wire, such as that shown in Fig. 2. Elements 15 consist of a straight shank having at one end a head formation preferably produced by flattening the shank a short distance from the end and leaving a portion of the shank at full diameter to provide the head. Such a head is shown at 15A with the flattened portion at 15B.

At the other end of the shank, the wire is bent at a right angle as at 16 and then bent up as at 17 at a right angle to the plane of portions 15 and 16. The wire beyond is then bent downwardly as at 18 parallel to but spaced from portion 17, the spacing being such that the parts 17 and 18 will resiliently grip the edge of a strip

2

11. The extreme end of part 18 may then be bent back along part 16 as a finishing expedient.

These elements 15 are inserted in the strips 11 as shown in Fig. 1. That is, the shank portion passes through both strips and then the element partially rotated so that the parts 17 and 18 grip the edge portion of the upper strip 11 and thereby maintain the element rigid with this particular strip. The free end of element 15 with the head 15A extending through the lower strip 11 is then fixed against retraction by means of the device shown in detail in Figs. 4 to 6.

This device consists of a flat plate 20 having one end 20A turned up to act as a handle and as a stop for a slide 21.

The plate 20 is provided with a key-hole slot 20B so located that the slide 21, when moved against stop 20A, will expose the entire slot and its enlarged end 20C. When the head 15A on element 15 is passed through the portion 20C of the slot 20B, it may be moved into the narrow portion of the slot and prevented from retraction by moving the slide 21 over the slot portion 20C.

25 Figs. 3 and 5 show the locked and unlocked portions of the slide and element 15.

The modification shown in Fig. 7, shows a similar construction in which a single wire member 110 has its ends 115 bent at right angles to the main portion and parallel. These ends 115 will be headed as shown in Fig. 4 and held in the strips 11 by similar plates 20.

In this form, the mid portion of the body of element 110 is provided with a bent formation 110A gripping the edge of the strip 11.

35 In preparing sheets, leaflets, and the like for mounting in the binder, the thin wires 15 and 115 may be used as punches for a few sheets. For magazines, however, a punch or nail will be driven through to provide for passage of the element 15 or 115.

40 After the material has been traversed by the wire element and the latter inserted in the second strip 11, the plate 20 is then applied and locked.

45 Now having described the invention and the preferred embodiment thereof, it is to be understood that said invention is to be limited, not to the specific details herein set forth, but only by the scope of the claims which follow.

I claim:

1. In a paper binder having a cover with binding strips secured at the sides of the back cover portion, a paper securing element consisting of 55 piano wire having at one end a head and at

the other end being bent at right angles and again bent to provide a resilient gripping means arranged at right angles to the first bent portion and adapted to grip one of said strips, said wire adapted to traverse both strips, and means cooperating with said head to prevent retraction.

2. In a paper binder having a cover with binding strips secured at the sides of the back cover portion, a paper securing element consisting of a piano wire shank having at one end a head 10 and at the other end a portion bent at right angles, said portion being again bent at right angles to the plane of the before mentioned parts and back upon itself to provide a spring clip, said wire element being adapted to traverse both 15 of said strips and be fixed to one strip by means

of said clip, and a slotted plate adapted to co-operate with said head to prevent retraction from the other strip.

HERMAN T. ARENDTS.
